OIL FIRING UNIT

Erik Eklund, Malmo, Sweden, assignor to Aktiebolaget
Ljungmans Verksfader, Malmo, Sweden, a corpora-
tion of Sweden

Filed Nov. 9, 1959, Ser. No. 58,273

Claims priority, application Norway Sept. 3, 1959

Term of patent 14 years

(Cl. D81—2)

FIG. 1 is a perspective view showing one side and end of an oil firing unit embodying my new design;

FIG. 2 is an elevational view of the side of the unit opposite that shown in FIG. 1;

FIG. 3 is an elevational view of the end of the unit opposite the end shown in FIG. 1; and

FIG. 4 is a top plan view thereof.

I claim:

The ornamental design for an oil firing unit as shown.
